UNITED STATES PATENT OFFICE

LOUIS L. FOJTIK, OF NEEDVILLE, TEXAS

GUIDING DEVICE FOR PLOWS

Application filed January 5, 1929. Serial No. 330,643.

My present invention has reference to an improved plow construction.

The primary object of the invention is the provision of a gang plow with means whereby the furrow wheels as well as the tongue of the plow may be simultaneously turned to insure evenly distant furrows being made by the plow shares.

A further object is the provision of a means for this purpose that is arranged conveniently with respect to the driver or operator of the plow and which may be operated by the throw of a single lever.

A further object is the provision of a guiding device for plows which, with slight alterations may be readily attached to any ordinary gang plow construction.

To the attainment of the foregoing and many other objects which will present themselves the invention consists in the improvement hereinafter described and definitely claimed.

In the drawings:

Figure 1 is a top plan view of my improvement.

Figure 2 is a side elevation thereof.

Figure 3 is an enlarged sectional view on the line 3—3 of Figure 2.

Figure 4 is a detail elevation to further illustrate a manner in which the rod carrying lever is associated with the toothed rack and the manner in which the latter is pivoted to the plow beam.

Figure 5 is a view substantially similar to Figure 4 but illustrating a slight modification.

Figure 6 is a plan view of the rack.

Figure 7 is a sectional view approximately on the line 7—7 of Figure 5.

The plow shares are connected to the plow beam in the usual manner and the crank or arched axle is swung and held adjusted with respect to the plow beam by the usual lever. The plows and the adjusting lever have been omitted from the showing of the drawings as it does not form part of this invention.

Referring now to the drawings in detail, the numeral 1 designates the beam of an ordinary gang plow. In the present instance the beam is preferably in the nature of an I iron

and at its forward or front end is thickened downwardly and bifurcated to provide what may be termed parallel arms and which for distinction are indicated by the numerals 2 and 3, respectively. Fixedly secured to the confronting faces of these arms 2 and 3, at the front of the beam 1 there are arched plates 4 that provide guides for the tongue 5. The tongue 5 is pivoted between the arms 2 and 3. The pivot for the tongue is in the nature of an elongated bolt member 6. The lower portion of the bolt is rounded and the same has a shoulder 7 to rest against the top of the beam on what I have termed the upper end of the arm 2. Between the arms 2 and 3 and the tongue 5 there are spacer washers 8 and a cotter pin 9 is passed through the pivot 6, and contacts with the lower arm 3 to hold the said pivot from longitudinal movement. The upper portion of the pivot 6 is squared, as at 10, and arranged on this squared portion there is a lug or finger 11 which has a squared bore for the reception of the said squared end of the pivot. A binding element 12 passes through the lug or finger and contacts with the pivot for adjustably sustaining the said lug or finger on the pivot.

Between the sides of the beam 1 and the arched guide plates 4 there are brace rods 13 and preferably the securing means between the brace rods and the ends of the guides 4 are in the nature of bolts 14 which, of course, are in the path of contact with the tongue 5 and limit the swinging of the tongue on the pivot 6. The tongue 5 is, of course, designed to have associated therewith the means for attaching draft animals or a tractor to the plow.

The arched or cranked axle for the ground wheel 15 is indicated by the numeral 16 and is, of course, journaled in suitable bearings beneath the under face of the beam 1, and slightly to the rear of the shaft 16 on one side of the beam 1 I pivot, as at 17, the central and depending portion or arm 18 of a segmental rack 19. There is pivoted, as at 20, at a point approximately central of the arm 18, the lower end of a lever 21. The lever carries a spring influenced handle operated

dog 22 to engage in any of the teeth of the segmental rack 19. The lever, in a line with its pivotal connection with the arm 18 of the rack 19 has pivotally secured thereto a rod 23. This rod is made up of at least two sections which have their confronting ends provided with different hand pitch threads to be engaged by a turn buckle 24. The outer end of the rod is bifurcated, as at 25, and receives therein the lug or finger 11 while a pivot 26 connects the said end of the rod to the lug or finger.

Arranged for lateral adjustment on the beam 1, between the pivotally supported rack 15 and the inner end of the tongue 5 there is a mount for the front furrow wheel 27 of the improvement. The furrow wheel 27 is journaled on the usual axle 28 which is provided with an upstanding stem 29. This stem 20 passes through the opening in a boss or enlargement in one end of a slotted plate 30 that is arranged in parallelism with the horizontal portion 28 of the axle and passing through the beam and through the slot of 25 the plate 30 there are binding means which are in the nature of bolts 31 that are engaged by suitable nuts. By this arrangement it will be seen that the furrow wheel 27 may be longitudinally adjusted with respect to the beam 30. The stem or standard 29 has arranged for vertical adjustment thereon a lug or finger 32. A binding element 33 passes through the said lug or finger and frictionally engages with the stem 29. The lug or finger has pivotally secured thereto the bifurcated end of a rod 34, the second end of the rod being pivotally connected, at 35, to the lever 21. The rod 34 is also made up of at least two sections whose ends are provided with oppositely hand pitched threads which are engaged by a turn buckle 36.

The rear furrow wheel of the improvement is indicated by the numeral 37, the mount therefor being in the nature of a crank stem. The vertical arm 39 for the mount passes through a suitable bearing opening in the rear of the beam 1. Suitable means is provided for holding the arm or standard 39 from longitudinal movement through the beam 1 and 50 this means may also provide for the vertical adjustment of the said standard through the said beam 1.

Mounted for vertical adjustment on the standard 39 there is a lug or finger 40. A binding element 41 passes through the lug or finger and contacts with the standard 39. The lug or finger has pivotally secured thereto one end of a rod 42. The second end of this rod is pivoted, as at 43, to the rack 19 at approximately the juncture of the said rod with the arm 18. The rod 42 is made up of at least two sections which have oppositely hand pitched threaded ends which are engaged by a turn buckle 44.

By bringing the dog 22 out of the teeth of

the rack 19 and by swinging the lever 21 on its pivot 20 a longitudinal movement will be imparted to the rod 34 which will cause the furrow wheel 27 to turn with the stem 29 so that the wheel 27 will be properly retained in the furrow made by the plow share without swinging the tongue or turning the rear furrow wheel 37. By permitting the dog to engage with the rack 19 the swinging of the lever will also swing the rack and consequently impart a longitudinal movement to the rods 23, 34 and 42 and thereby simultaneously swinging the tongue 5 and turning the furrow wheels 27 and 37. By arranging the slotted plate 30 on the vertical stem 29 on the axle 28 it will be apparent that the furrow wheel 27 may be adjusted toward or away from the beam 1 so that the wheel 27 will properly travel in the furrow therefor.

In Figures 5, 6 and 7 I have illustrated a slight modification, the features of distinction being that all of the rods are maintained at the same plane which is not true with respect to the construction previously described. On the plow beam 45 I fix the straight end of an offset plate 46. To the upper end of the plate 46 I pivot, as at 47, the arm 48 of a segmental rack 49, the said pivot also connecting the plate with a lever 50. The lever is provided with a spring influenced handle operated dog 51 to engage with the rack 49. The lever, in a line with the rack 49, has pivoted thereto an adjustable rod 52 whose outer end is connected with the mount for the front furrow wheel, the rack at the center thereof having pivotally connected thereto an adjustable rod 53 which is connected with the mount for the rear furrow wheel. The lower end of the arm 48 has pivotally connected thereto an adjustable rod 53' which is connected to the pivot for the tongue of the implement. The operation of this construction is precisely similar to that previously described.

It is believed that when the foregoing description has been carefully read in connection with the accompanying drawings the simplicity and advantages of my improvement will be understood and appreciated by those skilled in the art. Obviously I do not wish to be restricted to the precise details herein set forth and, therefore, hold myself entitled to make such changes therefrom as fairly fall within the scope of what I claim.

Having described the invention, I claim:

A three wheeled plow which includes a ground wheel and front and rear furrow wheels, and a tongue which is pivotally secured to the beam of the plow, the pivot for the tongue having a square stem extension, a finger adjustably secured on said stem, a rod pivotally secured to the said finger, a toothed segment having a depending arm which is pivoted to the plow beam, a lever pivoted to the arm and which pivot connects the rod to the lever and arm, a spring influenced dog

carried by the lever to engage the rack, an angle shaft for the front furrow wheel, a slotted plate through which the vertical stem of the shaft passes and which is adjustably secured to the plow beam, a finger adjustably secured on the vertical stem of the shaft, a rod pivoted to the finger and pivoted to the lever, an angle axle for the rear furrow wheel having its vertical member journaled through the beam, and an adjustable finger on said vertical member and a rod pivotally connected to the finger and pivotally connected to the rack.

10 In testimony whereof I affix my signature.

LOUIS L. FOJTIK.
